UNITED STATES PATENT OFFICE.

PHILIP G. LUCAS, JR., OF ST. LOUIS, MISSOURI.

DESIGN FOR A COMBINED BREAD-BOX AND FLOUR-BIN OR SIMILAR ARTICLE.

59,499.

Specification for Design.

Patented Oct. 25, 1921.

Application filed April 26, 1920. Serial No. 376,880. Term of patent 14 years.

To all whom it may concern:

Be it known that I, PHILIP G. LUCAS, Jr., a citizen of the United States of America, residing in the city of St. Louis and State of Missouri, have invented a new, original, and ornamental Design for a Combined Bread-Box and Flour-Bin or Similar Article, of which the following is a specification, reference being had to the accompanying drawing, forming part thereof.

Figure 1 is a perspective view showing the front and side walls of my new design. Fig. 2 is a plan view of said Fig. 1.

I claim:

The ornamental design for a combined bread box and flour bin, or similar article, as shown.

PHILIP G. LUCAS, JR.
